UNITED STATES PATENT OFFICE.

FREDERIC LLOYD, OF LEWISTON, MAINE, ASSIGNOR TO WILLIAM C. HUNNEMAN, OF BROOKLINE, MASSACHUSETTS.

DESIGN FOR A BEDSPREAD.

44,010.

Specification for Design.

Patented May 13, 1913.

Application filed March 19, 1913. Serial No. 755,547. Term of patent 14 years.

To all whom it may concern:

Be it known that I, FREDERIC LLOYD, a subject of George V, King of Great Britain and Ireland, a resident of Lewiston, in the county of Androscoggin and State of Maine, have invented a new, original, and ornamental Design for Bedspreads, of which the following is a specification, reference being had to the accompanying drawing, forming part thereof.

The figure is a plan view of a portion of a bedspread showing my new design.

I claim:

The ornamental design for a bedspread, as shown.

FREDERIC LLOYD.
